[57] CLAIM

The ornamental design for cordless portable telephone,
as shown and described.

DESCRIPTION

FIG. 1 is a perspective view of a cordless portable telephone showing my new design;

FIG. 2 is front elevational view thereof;

FIG. 3 is a right side elevational view, the left side being
a mirror image thereof, wherein the clip, having a central
opening for the loudspeaker, has been lifted to an
open position;

FIG. 4 is a rear perspective view thereof;

FIG. 5 is a top plan view thereof;

FIG. 6 is a bottom plan view thereof; and,

FIG. 7 is a rear perspective view thereof, the broken
line showing of an attachable module being for illustra-
tive purposes only.

FIG. 1

FIG. 2

FIG. 3

FIG. 4

FIG. 5

FIG. 7

FIG. 6
